UNITED STATES PATENT OFFICE.

WILLIAM L. GREELEY, OF NEW YORK, N. Y.

ADJUSTABLE ANCHOR DEVICE.

No. 846,995.

Specification of Letters Patent. Patented March 12, 1907.

Application filed October 30, 1906. Serial No. 341,359.

To all whom it may concern:

Be it known that I, WILLIAM L. GREELEY, a citizen of the United States of America, and a resident of the borough of Manhattan, city, county, and State of New York, have invented certain new and useful Improvements in Adjustable Anchor Devices, of which the following is a specification.

My invention relates in general to means for fastening objects to a wall or body of plastic material; and more specifically comprises an improved apparatus for attaching ladders to walls or chimneys formed of what is known as "reinforced concrete." This reinforced-concrete construction comprises a body of plastic cement built up by being placed in forms or molds, and in the case of a tall structure, like a chimney, it is extremely difficult to place a long series of bolts or anchor-irons therein in process of construction and have the same properly alined when the chimney is complete and a ladder is attempted to be attached thereto.

My invention overcomes these and other difficulties encountered in this and similar attempts to anchor a long exterior construction to a concrete wall.

The best form of apparatus embodying my invention at present known to me is illustrated in the accompanying sheet of drawings, in which—

Figure 1 is a side view of a portion of the chimney with ladder thereon. Fig. 2 is a similar view at right angles to the plane of Fig. 1. Fig. 3 is a detail side view of my improved form of anchor-iron with rods or bolts inserted therein, partly broken away. Fig. 4 is a plan view of the same. Fig. 5 is an end view of Fig. 4. Fig. 6 is a horizontal section through a portion of the chimney-wall and ladder, showing in enlarged detail the completed construction with the ladder in place.

Throughout the drawings like reference-figures indicate like parts.

1 is any form of chimney or other wall 2; the anchor-iron, having a flat body portion and near either end a pair of jaws 3, which form slotted portions of said complete anchor-iron. These jaws extend at right angles to the flat body portion of the anchor-iron, and each jaw has a keyway 4 formed in its inner surface parallel to the body of the anchor-iron. Each of these keyways 4, &c., is preferably of the same cross-section and the same distance from the body of the anchor-iron. As shown in Fig. 5, said keyways

are adjacent to the flat body portion of the anchor-iron.

5 5 represent nuts, which are preferably of square or rectangular form, adapted to slide 6 in keyways 4 and fill the same.

6 6 are threaded rods of proper size to be inserted between the jaws of the anchor-iron and be screwed into the nuts 5.

7 7 are jam-nuts mounted on the threaded 65 rods 6 and adapted to be screwed down against the slotted anchor-iron and lock the parts in their proper relation.

8 8 are any convenient form of clamps mounted on the exterior portion of the 70 threaded rods and adapted to grasp the sides of the ladder 10.

9 9 are nuts forcing the clamps 8 into engagement with the sides of the ladder and holding them there. 75

The operation of my invention is as follows: In building the chimney at each proper point in the process of building an anchor-iron is laid in the cement in the position shown in Fig. 6, so that the slots extend 80 to the surface of the chimney-wall. Before inserting each anchor-iron two nuts 5 are placed in position in the keyways 4 at the base of the slots between the jaws. The slotted jaws extending to the surface of the 85 wall, little or no cement gets between them, and such small portions of cement as do creep in can easily be dug out. After the chimney is completed the threaded rods 6 are fished into the anchor-irons and screwed 90 into the nuts 5. The ladder 10 is placed in position, the rods and clamps are properly adjusted to hold said ladder straight and true, and the jam-nuts 7 and 9 are all set up hard, locking the parts firmly in their ad- 95 justed positions.

The advantages of my invention comprise the firmness of the anchoring means and the ease of adjustment in every direction by which a perfect alinement of the ladder or other object to be supported is secured. If the anchor-irons 2 are a little out of line with reference to the plane of Fig. 1, the nuts 5 can be shifted in the slotted keyway, so as to bring all the rods 6 in vertical alinement. If the surface of the wall is a little out of true or some of the anchor-irons are embedded a little too deeply or not quite deeply enough, the proper alinement of the ladder with reference to the plane of Fig. 2 105 can be obtained by not screwing the rods 6 completely into the nuts 5 or by adjusting

the clamping devices on these rods or by both methods combined. The parts being duplicates and interchangeable, they can be manufactured at small cost and easily assembled.

It is evident that various changes could be made in the details of construction illustrated and described, so long as the underlying principle of my invention is employed. Other forms of clamping device might be employed, the configuration of the anchor-iron might be changed, other means for retaining the nuts in the slotted anchor-irons might be substituted for those shown, and similar modifications in matters of detail readily made by those skilled in the art.

Having therefore described my invention, I claim—

1. The combination of an anchor-iron adapted to be embedded in a wall and having separate slotted portions extending outward toward the surface of the wall, two nuts fitting into the slotted portions, means for retaining said nuts therein but permitting movement of the same toward or from each other, and screw-threaded rods adapted to be inserted in said slotted portions and screwed into said nuts, together with sliding clamps mounted on the outer ends of said rods and a ladder adapted to be grasped by said clamps.

2. The combination of an anchor-iron adapted to be embedded in a wall and having

separate slotted portions extending outward toward the surface of the wall, two nuts fitting into the slotted portions, means for retaining said nuts therein but permitting movement of the same toward or from each other, and screw-threaded rods adapted to be inserted in said slotted portions and screwed into said nuts, together with sliding clamps mounted on the outer ends of said rods and a ladder adapted to be grasped by said clamps, the outer ends of said rods being threaded and nuts mounted on said threaded portion and engaging said clamps.

3. The combination of an anchor-iron adapted to be embedded in a wall and having separate slotted portions extending outward toward the surface of the wall, two nuts fitting into the slotted portions, means for retaining said nuts therein but permitting movement of the same toward or from each other, and screw-threaded rods adapted to be inserted in said slotted portions and screwed into said nuts, together with sliding clamps mounted on the outer ends of said rods and a ladder adapted to be grasped by said clamps, and jam-nuts mounted on the inner ends of said rods interiorly of the anchor-iron.

Signed at New York, N. Y., this 25th day of October, 1906.

WILLIAM L. GREELEY.
